ATT.

UNITED STATES PATENT OFFICE.

ADOLPH J. BIEGACKI, OF CLEVELAND, OHIO.

DOOR OR WINDOW FASTENER.

1,354,876.

Specification of Letters Patent.

Patented Oct. 5, 1920.

Application filed February 26, 1920. Serial No. 361,489.

To all whom it may concern:

Be it known that I, ADOLPH J. BIEGACKI, a citizen of the United States, residing at Cleveland, in the county of Cuyahoga and 5 State of Ohio, have invented certain new and useful Improvements in Door or Window Fasteners, of which the following is a specification.

This invention relates to an improved 10 fastener and has for its object to provide a device which is so constructed as to permit of it being applied to either a door or a window. The peculiar construction of the fastener allows the door or the window to 15 be opened slightly.

In constructing the device the idea has been to provide a means whereby a door may be opened only sufficiently to permit conversation to be had and in the case of a 20 window to allow ventilation and thereby prevent the entrance of unauthorized persons.

Further objects of the invention are in the provision of a device which will be 25 simple and cheap of manufacture, durable, efficient in operation and attractive in appearance.

The invention further consists in the certain construction and combination of parts 30 hereinafter illustrated, described and particularly pointed out in the appended claims.

In the drawings Figure 1 is a plan view of the device shown attached to a door casing; Fig. 2 is a front elevation and Fig. 3 35 is a sectional detail on the line 3—3 of Fig. 2.

The invention comprises the following members: keeper A, which is attached to the door or window, and a bar B which is pivotally secured at one of its ends to a hinge member C secured to the door casing. The keeper A consists of a rectangular plate 4 secured to the door by screws 5 and provided with a pair of fingers 6 which extend at 45 right angles to the plate 4. Said fingers are spaced from each other sufficiently to provide a rectangular slot 7 which is restricted at its outer end by means of projections 8, and at its inner end said opening is extended laterally as shown at 9 for a purpose to be 50 hereinafter described. The fastener bar B is preferably made of heavy wire which is so formed as to provide at one end lateral extensions 10, a restricted portion 11 and at a 55 point near its opposite end with a further restricted portion 12, and the separate ends

of the wire are bent laterally and in opposite directions to each other and are pivotally confined within eyes 14 on the hinge member C, which consists of a plate 15 provided with 60 apertures whereby the same may be secured in a fixed position upon the door casing.

In operation the fastener bar is swung so that it approaches a plane parallel to the door when the door is in the closed position. 65 The restricted portion 12 is snapped between the fingers 6 of the keeper A. It will be noted that the space between the fingers of the keeper A is of lesser width than the width of the portion 12 of the fastener bar, 70 but due to the resiliency of the wire the bar can be sprung therein. The door then may be swung open and in the direction of the arrow D a slight distance due to the fact that the portion 12 rides freely in the opening 7 of the keeper A and will continue to do 75 so until it meets the shoulder 20 of the bar when further movement is prevented until the portion 11 of the bar is moved or swung inwardly sufficiently to allow it to ride in 80 the opening 9 when the door may be further opened until the lateral projections 10 meet the corner formed by the fingers 6 and the plate 4 of the keeper A. When the device is not in use the bar B may be swung in the 85 reverse direction and it will then lie in a plane parallel to the door casing. When applied to a window the window may be opened until the projections on the bar stop against the keeper A. 90

It will thus be seen that a device is provided which will effectively accomplish the purpose set forth and that the device is capable of various modifications and I do not wish to limit myself in the construction 95 of the same further than is required by the state of the art or that which comes within the scope of the appended claims.

I claim:

1. A fastener for closures comprising a 100 swinging bar, and a keeper adapted to be fixed to the closure, said keeper having a pair of fingers with a slot between, said slot being open at its outer end and enlarged in width at its inner end, and the bar 105 being slidable in said slot and having projections at its free end which will not pass through the enlarged part of the slot, and shoulders intermediate its ends which are engageable with the restricted part of the 110 slot to form an intermediate stop permitting only slight opening of the closure.

2. A fastener for closures, comprising a swinging bar adapted to be pivoted at one end to the casing of the closure, and a keeper adapted to be fixed to the closure, 5 said keeper having a pair of fingers with an open slot between in which the bar is slideable the outer ends of the fingers projecting toward each other to restrict the width of the slot, and the bar comprising opposite

spaced spring members which may be 10 sprung between the ends of the fingers and into the slot.

In testimony whereof I do affix my signature in presence of two witnesses.

ADOLPH J. BIEGACKI.

Witnesses:

MARTIN BUDNIAK,

JOHN A. BOMMHARDT.
